AIR-COMPRESSOR SYSTEM.

1,261,041.

Specification of Letters Patent.

Patented Apr. 2, 1918.

Application filed January 30, 1915, Serial No. 5,234.

To all whom it may concern:

Be it known that I, CARL E. L. LIPMAN, a citizen of the United States, residing at Beloit, in the county of Rock and State of Wisconsin, have invented certain new and useful Improvements in Air-Compressor Systems, of which the following is a specification.

This invention relates in general to systems for generating and storing fluid under pressure, and has more particular reference to an air compressor system in which air is compressed and stored in a reservoir under a desired pressure, from whence it may be used when required for inflating automobile tires or for any other desired purpose.

In systems of this general character it is customary to drive the air compressor by an electric motor which is automatically controlled by a pressure-actuated switch so that the compressor is set in operation when the pressure in the reservoir drops to a predetermined minimum, and is subsequently thrown out of operation when the pressure has been raised to a predetermined maximum.

It will be manifest, however, that in systems of this character, if the compressor is connected directly with the storage reservoir so that as soon as the compressor is started it immediately begins to act against the pressure in the tank, a very heavy load will be imposed upon the compressor and the driving motor before the motor has time to speed up. It has been necessary, therefore, to install a motor much larger than is necessary to operate the compressor at high speed in order that the motor might be able to start the compressor against the pressure in the reservoir without being burned out.

One of the primary objects of my present invention is to provide in an air compressor system means which will automatically permit the compressor to start against a minimum load only slightly in excess of atmospheric pressure so that the compressor and driving motor may speed up before the compressor begins to work against the pressure in the reservoir.

Another object of the invention is to provide simple means for accomplishing the above result, which shall be certain and accurate in operation and which will open the pressure line from the compressor to the atmosphere each time the compressor stops,

thereby insuring that the compressor will start each time under a minimum load.

A further object of this invention is to provide means in the pressure line between the compressor and the storage reservoir in which moisture, oil, etc., carried by the air from the compressor will be collected and from which it will be automatically discharged between successive operations of the compressor.

Other objects and many of the attendant advantages of this invention will be readily appreciated as the invention is better understood by reference to the following description when considered in connection with the accompanying drawings.

Referring to the drawings—

Figure 1 is a side elevation of a system embodying my invention;

Fig. 2 is a sectional view on the line 2—2 of Fig. 1; and

Fig. 3 is a sectional view on the line 3—3 of Fig. 2.

Referring to the drawings, reference character 5 indicates an air compressor of any well known or preferred type which is driven from a motor 6 through a gear-train 7. 8 represents a storage reservoir of any desired capacity into which air under pressure is forced by the compressor through the pressure line 9. The air may be withdrawn for use from the reservoir through a pipe 11, the supply of air being controlled by a manually operable valve 12. The motor driving circuit, comprising the generator 13, includes an automatic pressure controlled switch 14 of any preferred type which is connected with the storage reservoir 8 so that when the pressure in the reservoir drops to a predetermined minimum the switch will close, thereby automatically starting the compressor, and when the pressure in the reservoir has been raised to a predetermined maximum the switch will automatically open to stop the compressor.

The pipe 9 instead of being connected directly with the reservoir as is customarily done, discharges into the upper end of a cylinder or bore 15 formed at one side of a chamber 16 which is connected to the storage reservoir by a nipple 17. The chamber 16 is divided by a partition wall 20 into the bore 15 and the larger compartment 18, communication being established between the bore and the compartment through a plu-

rality of ports 19 and 21, respectively. A check valve 22 is interposed between the compartment 18 and the reservoir to prevent back-flow of pressure from the reservoir into the compartment, and a pressure gage 23 of any preferred type is mounted upon the chamber 16 by means of a pipe 24, so that the gage will register the pressure in the reservoir.

- 10 The lower end of the bore 15 below the port 21 is closed by a hollow plug 25 provided with a tapered valve seat 26 which is adapted to be closed by a valve 27 carried by a plunger 28 which is normally held in the elevated position shown in Fig. 2 by a coiled expansion spring 29. A plunger 31 is disposed in the bore 15 above the plunger 28 and is normally held in the position shown in Fig. 2 by a coiled spring 32.
- 20 When the compressor is idle the pressure in the reservoir is prevented from backing up in the line by the check valve 22, while the compartment 18 is open to the atmosphere through port 21 and the hollow plug 25. Assuming now that the current is turned on to start the motor the compressor will begin to operate against a pressure equal to atmospheric pressure plus the tension of the light spring 32, thus imposing only a small load on the compressor and motor. As the pressure increases in the pipe 9 the plunger 31 will be depressed below the port 19, thereby permitting the air to enter the compartment 18. Downward movement of the plunger 31 will, of course, compress the spring 32 and when the plunger 31 has been moved downwardly as far as the port 19 the spring 32 will overcome the pressure of the spring 29 and close the valve 27 against its seat. The air from the compressor will enter the compartment 18 against an initial pressure only slightly above atmospheric pressure, and while the compartment 18 is filling up the motor and compressor will have time to speed up to the required velocity to work against the pressure in the reservoir 8. When the pressure in the compartment 18 exceeds that in the storage reservoir the check valve 22 will, of course, open against the force of its spring and permit the pressure to be delivered into the reservoir.
- 55 When the compressor is stopped the pressure in the pipe 9 will diminish, whereupon spring 32 will return plunger 31 to the position shown in Fig. 2, and spring 29 will open the valve 27, permitting the pressure in the compartment 18 to escape to the atmosphere. The pressure in the compartment 18 is, therefore, automatically relieved each time the compressor stops, with the result that the compartment 18 must be filled and the pressure therein must be gradually raised before the compressor and motor will be subjected to their normal working load.

This construction obviously gives the motor and compressor sufficient time to develop a momentum with which the pressure in the reservoir may be overcome, and a much smaller motor can be used in this system than could be used in a system in which the compressor was connected directly to the storage reservoir so that the motor would be subjected on starting to its normal working load.

75 The compartment 18 also serves another purpose, in that any oil or moisture in the air delivered into the compartment will be retained therein and subsequently discharged therefrom through the port 21 and the plug 25. I prefer to provide a baffle plate in the compartment 18 to deflect the incoming air and facilitate the deposit of oil and moisture in the compartment. Another baffle plate 34 which also serves as a 85 strengthening or reinforcing member is preferably disposed substantially centrally of the compartment 18.

90 While I have used the term air throughout the specification as defining the fluid to be handled by the system, it should be understood that my invention is not restricted to systems in which air is employed but is equally adapted for use in systems in which water or other fluids are employed.

95 It is believed that the construction and operation of my invention will be understood from the foregoing without further description and it should be manifest that by the use of this system a considerable saving in the initial cost of the motor and in the running expense of the motor is effected.

100 I claim:

1. In a fluid compressor system, the combination of a compressor, a storage reservoir and connections between said compressor and reservoir comprising a chamber connected with the reservoir, a bore disposed at one side of said chamber and connected at its upper end with the compressor and at its lower end with the atmosphere, a port establishing communication between the lower end of said chamber and said bore, a second port establishing communication between said chamber and bore near the upper end thereof, a valve adapted to shut off communication between the lower end of said bore and the atmosphere, a spring for normally unseating said valve, a plunger disposed in said bore and normally covering said upper port, and a spring disposed between said valve and said plunger adapted to yield under the pressure exerted by said compressor to thereby uncover said upper port and close said valve. 115

120 2. In a fluid compressor system, the combination of a compressor, a storage reservoir and connections between said compressor and reservoir comprising a chamber connected with the reservoir, a bore dis-

posed at one side of said chamber and connected at its upper end with the compressor and at its lower end with the atmosphere, a port establishing communication between the lower end of said chamber and said bore, a second port establishing communication between said chamber and bore near the upper end thereof, a valve adapted to shut off communication between the lower end of said bore and the atmos- 5

phere, a spring for normally unseating said valve, and means in said bore normally covering said upper port and connected with said valve for closing said valve and opening said upper port upon admission of air 15 under pressure above said means.
